[57] **CLAIM**

The ornamental design for a sway bar tape measure, as shown and described.

DESCRIPTION

FIG. 1 is a front plan view of the sway bar tape measure according to this invention;

FIG. 2 is a rear view; and,

FIG. 3 is a side view.

The top plan view of the sway bar tape measure is a flat plane, the bottom plan view being identical.

FIG. 1

FIG. 2

FIG. 3
